UNITED STATES PATENT OFFICE.

CHARLES U. CARPENTER, OF NEW YORK, N. Y.

SAFE.

No. 882,995.

Specification of Letters Patent. Patented March 24, 1908.

Application filed October 14, 1907. Serial No. 397,371.

To all whom it may concern:

Be it known that I, CHARLES U. CARPENTER, of New York, in the county of New York and in the State of New York, have invented a certain new and useful Improvement 5 in Safes, and do hereby declare that the following is a full, clear, and exact description thereof, reference being had to the accompanying drawings, in which—

Figure 1 is a front elevation of a safe embodying my invention, the door being shown closed; Fig. 2 is a side elevation, partly in section, of the safe shown in Fig. 1; Fig. 3 is a front elevation, the door being open. Figs. 10 4 and 5 are respectively a side elevation of a plunger, and a plan view of a die used in forging my safe body; Fig. 6 is a side elevation of one of the two sections of the said die; Fig. 7 is a side elevation showing the 15 plate, to be forged, in position between the plunger and die, the front die section having been removed; and Fig. 8 is a view similar to Fig. 7, the parts being shown as they appear at the completion of the forging operation.

The object of my invention has been to provide a safe which shall be exceptionally strong to resist the attacks of burglars, shocks due to the falling of the safe, or to the 20 collapse of a building, and to resist fire and similar causes; and to such ends my invention consists in the safe hereinafter specified.

Prior to my invention, so far as I am aware, all safes have been made of one or the 25 other of two general constructions. First, safes have been made of sheets of metal either welded together or secured together as by bolts and rivets, and usually the walls of such safes have been made hollow, and 30 material offering more or less resistance to heat has been placed inside the walls. Safes of this construction occasionally fail from one of several causes. The sheet metal walls, being comparatively thin, are occasionally 35 penetrated by a burglar and explosive is introduced, which the walls, owing to their lack of strength, are unable to withstand. The bolts and rivets are a source of weakness; they may be started by an explosion 40 and may be drilled out. If the building in which the safe is placed collapses, owing to fire or earthquake, and the safe falls to the ground, the shock is liable to distort the safe, at least enough to admit fire to its 45 contents. The same result may follow the falling of the walls of a building upon the safe

or on the ground. Second, in order to overcome the foregoing objections, attempts have been made to so construct safes that the body of the safe shall be made of a single 50 piece of metal. Safes have been constructed in this manner by casting the body of the safe, the interior recess being formed by the mold. Safes constructed in this manner are 55 objectionable, however, because blow holes and other defects frequently occur in the metal, both in places where they can be seen, and also concealed beneath the surface of the metal. Those blow holes which can be seen result in the rejection of a large number of 60 the castings made for this purpose. Blow holes of apparently insignificant proportions are frequently much larger within the body 65 of the metal than would appear at the surface of the casting, and the safe may thus be 65 fatally weak even though it has only an apparently trifling blow hole on the surface. In those safes where no blow holes can be seen on the surface, and which are accordingly 70 put into use, there are frequently blow holes 75 and fissures within the body of the metal 80 which render the safe weak, but which, being invisible, do not prevent the casting from 85 being put into use. For these reasons the cast safes as heretofore constructed are not 90 entirely satisfactory.

It has been the object of my invention to overcome the objections to both of the above-described classes of safe construction. Notwithstanding the great thickness of the walls 95 of a safe compared with the size of the body thereof, I have conceived the making of a safe in a single piece by forging, a process by which I am enabled to get a safe whose walls are thoroughly homogeneous and without 100 defects of any kind, and a safe of much greater strength than is possible to obtain by casting.

In carrying my invention into practice I first obtain a heavy plate of steel, such as 105 armor plate. This plate I place over a die, the die consisting preferably of sections 11 and 12, which form between them a recess 13 of the shape which it is desired the safe body 110 to have. This recess I prefer to form tapering in a downward direction, although it may have any desired shape. It may be circular or rectangular, and cylindrical or frustoconical. The two sections of the die are united by bolts 14 so that the die may be 115 separated if desired to release the forged safe body. The die may, however, be formed in

a single piece if desired. This die is seated beneath a hydraulic press, steam hammer or other similar device. The press or hammer carries a plunger 15 of the shape which it is desired to form the interior of the safe body. The plunger 15 is preferably tapering to enable it to be readily released from the forged safe body. It may, however, have no taper. In forging the safe body the plate 16, of 10 armor plate from which the safe body is to be forged, is laid over the die 12, and the plunger 15 forced down by the press or hammer until the plate completely conforms to the interior of the die. The forged safe body is now removed from the die, the die sections being separated if necessary.

The next step is preferably the turning or forming of the rabbets or grooves 17 in the body of the safe to receive the corresponding 20 shoulders 18 on the door. The members 19 of the hinge which are to be on the body may, if desired, be forged on the body, but I prefer to make them separately and attach them as by bolts 20. The door 21 is preferably formed of a single forging, and its hinge member 22 is preferably formed integral therewith. The door is provided with bolts 23, or other form of lock, as may be desired. 25 The particular form of lock is not essential. The safe body is preferably mounted upon a wheeled base 24 in any desired manner as by bolts passing into the base from within the body. Shelving 25 of any desired construction is provided within the safe.

30 It will be observed that my safe has among others the following advantages: The body and door each being made of a single forging can be made homogeneous and free from blow holes or other defects so that such blow holes cannot be used by a burglar to effect an entrance into the safe nor to introduce ex-

plosive, and so that the safe shall be strong against explosion effected in any other way. The safe is amply strong to withstand either the shock of a fall from an upper story of a 4 building, or that due to the falling upon the safe of a wall or other portion of a building. There are no plates to be twisted or warped in case of fire, and no bolts or rivets to be 5 started in case of explosion or shock, or to be drilled. Since by forging it can be made practically certain that the metal is free from defects, the percentage of loss from defective safe bodies is so small as to be negligible. The rabbets or grooves in the safe body, instead of being formed on a piece of metal 5 separate from those forming the sides of the body (as is usual) can be formed in the one piece of metal constituting the safe body.

It is obvious that various changes can be 6 made in the above-described construction which will be within the spirit of my invention. I have illustrated that construction which I deem to be best, and that mode of making it which I consider most effective; 6 but the details may be changed within wide limits. For instance, it would be the equivalent of the above-described method of making the safe to form an ingot under pressure so as to expel all bubbles and then to cut the 7 body of the safe out of the ingot without further forging.

I claim:

A safe, consisting of the combination of a body formed of a single piece of forged steel, with a door.

In testimony that I claim the foregoing I have hereunto set my hand.

CHARLES U. CARPENTER.
